BALANCED VALVE FOR GAS-ENGINES.

SPECIFICATION forming part of Letters Patent No. 699,372, dated May 6, 1902.

Application filed October 5, 1900. Serial No. 32,064. (No model.)

To all whom it may concern:

Be it known that I, SILAS H. DYER, a citizen of the United States, residing at Pawtucket, in the county of Providence and State of Rhode Island, have invented a new and useful Improvement in Balanced Valves for Gas-Engines, of which the following is a specification.

This invention has reference to an improvement in the construction of the valve for gas-
engines controlling the admission of the explosive mixture to and the discharge of the same from the cylinder; and it consists in the peculiar and novel construction of the valve and valve-casing whereby pressure on the valve caused by the explosion is balanced, as will be more fully set forth hereinafter, and more particularly pointed out in the claims.

Figure 1 is a side view of the end of the engine-cylinder provided with the valve. Fig. 2 is a vertical transverse sectional view of the same, taken on the line xx of Fig. 3. Fig. 3 is a top view of the valve, the cap of the valve-case being removed.

Similar marks of reference indicate corresponding parts in all the figures.

In the drawings, a indicates part of the engine-cylinder, a' the piston, and b a circular disk secured to the end of the cylinder. The inlet-passage b' and the outlet-passage b^2 are formed in the disk and extend from the periphery to one of the flat sides of the disk. In the drawings the inlet and outlet passages extend to the upper surface of the disk b . A series of openings b^3 b^3 extend through the disk. The valve-disk c , provided with the opening c' , is journaled in the center of the disk b . The stem c^2 , extending through the disk, has the lower end screw-threaded. The disk c^3 is secured adjustably by screw-thread engagement with the stem c^2 and held in the adjusted position by the lock-nut c^4 . The shaft c^5 of the valve c is journaled in the cap d , which is secured to the end of the cylinder and bears around the periphery on the disk b . The cap d has the chamber d' , which forms an explosion-chamber, which communicates through the openings b^3 b^3 in the disk b with the interior of the cylinder. In the construction shown in the drawings the cap d and disk b are shown secured to the end of the cylinder by the bolts d^2 d^2 .

The shaft c^5 is connected with and rotated

by a rotating part of the engine, preferably the crank-shaft, in the manner usual with explosive-engines. In rotating the valve c the opening c' in passing over the port of the inlet-passage b' admits the explosive mixture to the explosion-chamber d' . The mixture drawn by the piston passes through the openings b^3 b^3 into the cylinder. The rotation of the valve carries the opening c' beyond the port and cuts off the supply. The explosive mixture is now usually compressed by the return stroke of the cylinder and then ignited. The force of the explosion acts equally on the disk c^3 and on the disk of the valve c , because the pressure is equalized by the openings b^3 b^3 in the disk b , and the two disks are of the same diameter. The impact of the valve against its supporting-surface and the wear caused by such impact are avoided. When the opening c' passes over the port of the outlet-passage b^2 , the products of combustion may be expelled in the usual manner.

I do not wish to confine myself to the exact construction of the parts and their relations, as the same may be varied without departing from the essential feature of the invention.

Having thus described my invention, I claim as new and desire to secure by Letters Patent—

1. A rotatable valve for a gas-engine having two disks secured to a valve-stem, a body between the two disks containing the inlet and the outlet passages, an opening in one of the disks arranged to register with said passages as the valve rotates, and a chamber inclosing the valve, whereby the force of the explosion is exerted equally on the two disks, as described.

2. In a gas-engine, the combination with the cylinder, of a perforated disk, inlet and outlet passages in the disk, two valve-disks bearing on the opposite sides of the perforated disk and secured to a common valve-stem, the port c' , and a cap, as described.

3. A gas-engine valve having two disks secured to a valve-stem, inlet and outlet passages between the two disks, an opening in one of the disks, and a combustion-chamber inclosing both of the valve-disks, as described.

4. In a gas-engine, a cylinder having a perforated disk containing the inlet and outlet passages, a cap secured to the end of the cyl-

inder, a rotary valve-disk having an opening controlling the inlet and outlet ports, a valve-stem journaled in the perforated disk, and a disk secured to the end of the valve-stem and bearing on the opposite side of the perforated disk, as described.

In testimony whereof I have signed my

name to this specification in the presence of two subscribing witnesses.

SILAS H. DYER.
